UNITED STATES PATENT OFFICE.

EDWARD LESLIE, OF ORANGEVILLE, ONTARIO, CANADA.

ICE AND SNOW PLOW FOR RAILROAD-TRACKS.

SPECIFICATION forming part of Letters Patent No. 380,042, dated March 27, 1888.

Application filed July 2, 1887. Serial No. 243,251. (No model.)

To all whom it may concern:

Be it known that I, EDWARD LESLIE, of the town of Orangeville, in the county of Dufferin, in the Province of Ontario, Canada, gentleman, have invented a certain new and useful Improved Ice and Snow Plow for Railroad-Tracks, of which the following is a specification.

The object of the invention is to design an effective ice and snow plow which will loosen any hardened snow or ice immediately next to the track and remove the snow and ice in proximity to the inside of the rail and discharge the same a sufficient distance from the track to prevent it falling back; and it consists, essentially, in the peculiar combinations and the novel construction, arrangement, and adaptation of parts, all as more fully herein-after described and claimed.

2c Figure 1 is a perspective view of a portion of a car-truck provided with my improved ice and snow plow. Fig. 2 is a perspective detail of the frame on which the ice-plows and rail-scrapers are attached. Fig. 3 is a perspective 25 detail of the frame on which the flangers are attached.

In the drawings like letters of reference indicate corresponding parts in the different figures.

30 A represents the front axle of the truck. B are arms attached to or forming part of the frame C, and provided with suitable boxes to journal on the front axle, A, as shown.

D are plows attached to the frame C in such 35 a position that when the said frame is dropped down the plows will project below the rails close to the inside of each rail.

E are scrapers attached to and extending outwardly from the plows D in such a position 40 that when the frame C is dropped down the scrapers E will rest upon the top surface of the rail immediately in front of the wheels F, which are attached to the axle A.

G is a crank-shaft suitably journaled on the 45 truck-frame H, and provided with a lever, I, as shown. The cranks a of the shaft G are connected by suitable links to the frame C, so that by moving the lever I the frame C may be raised or lowered, as required.

50 J are flangers, curved as shown, and rigidly secured to the frame K, which is provided

with arms L, journaled on the axle M. It will be noticed that the flangers have each a downward projection, b, extending below the rails immediately next to the inside of each rail, so 55 as to gather up the snow and ice loosened by the plows D and discharge them over the rail clear of the wheels, the curved form of the flangers J constituting a spout which will convey the loosened ice and snow away from the 60 rail, as specified. As the flangers J and frame K, to which they are connected, are very heavy, I prefer to provide steam-power for raising and lowering the flangers. With that object I provide a steam-cylinder, N, and connect its 65 piston-rod O to one end of the beam P, the other end of which is suitably connected to the frame K by the link Q, which is so connected to the said frame K as to permit the lateral movement of the said frame without affecting 70 the piston-rod O, connected at the other end of the beam P. An elongated slot, d, made in the beam P permits the said beam to move longitudinally on its bearing R, thereby providing for the longitudinal adjustment of the beam 75 P as it is rocked on its bearing for the purpose of raising or lowering the frame K. By thus connecting the frame K to the piston-rod O, I am enabled to form a direct connection between the piston-rod and the beam P without 80 any fear of straining the piston-rod O, which is of course carried in suitable bearings. By journaling the frames C and K upon their respective axles I am able to locate the plows and flangers attached to them close to the rail, 85 as the frames on which they are carried follow the curve of the road, as they are supported from the same axis as the wheels which follow or precede them.

What I claim as my invention is—

1. The frame C, journaled on the axle of the truck-wheel, and having plows D and scrapers E attached to it, in combination with mechanism to vertically adjust the said frame, as specified.

2. The frame C, provided with arms B, journaled on the axle A, and having plows D and scrapers E attached to it, in combination with the crank-shaft G, connected to the frame C, and having a lever, I, attached to it, substantially as and for the purpose specified.

3. A flanger connected to a frame or arm

journaled on the truck-axle, and having a downward projection, *b*, formed on the said flanger, which extends outwardly beyond the outside of the truck-wheel, the frame *K*, provided with arms *L*, journaled on the axle *M*, in combination with the mechanism for imparting the vertical adjustment to the said flangers, substantially as and for the purpose specified.

4. The frame *K*, the beam *P*, the steam-cylinder *N*, and the link *Q*, arranged to connect the beam *P* with the frame *K*, so that the lat-

eral adjustment of the latter will not affect the beam, in combination with the piston-rod *O*, connected to the beam *P* and working within the steam-cylinder *N*, substantially as and for 15 the purpose specified.

Orangeville, June 18, 1887.

E. LESLIE.
